UNITED STATES PATENT OFFICE

2,608,801

VALVE

Ian M. Ridley, Los Angeles, Calif.

Application January 26, 1951, Serial No. 207,880

15 Claims. (Cl. 51—11)

1

This invention relates to sand blast control valves preferably in the form of nozzles or the like.

Conventionally, in sand blasting the control device for the blast has been located at or near the sand blast machine. It is preferable that the volume of the blast be controlled at the nozzle. Accordingly, this invention has among its objects the provision of a valve or nozzle suitable for sand blasting and capable of being regulated, shut off and/or turned on by the operator holding the sand blast hose.

Another object of the invention is the provision of a new and improved sand blast control valve.

Another further object of the invention is the provision in a new and improved sand blast control nozzle of new and improved water injection means.

Another further object of the invention is the provision, in a new and improved sand blast nozzle, of positive shut-off and/or snap action turn-on means.

Another further object of the invention is the provision in a sand blast valve of the desired character described of new and improved manipulatable adjustable means for controlling the blast.

Other objects of the invention include provision of new and improved axially manipulatable means for governing the flow of the blast of air and sand or the like with or without water, and of a valve of simple construction formed of a minimum of readily replaceable parts, each adapted for maximum effectiveness of operation and which are resistant to the scouring and erosive action of the blasted material.

It is also among the specific objects of the invention to provide a new and improved body for a sand blast valve, a new and improved rubber lining means therefor and a new and improved valve mechanism optionally comprising a portion of said lining means.

The invention likewise contemplates improvements in valve devices heretofore contemplated for generally similar purposes.

Other and further objects and advantages of my invention will become apparent from the drawings and the specifications relative thereto.

In the drawings:

Figure 1 is a sectional view of a preferred form of sand blast valve embodying this invention, the valve being closed.

Figure 2 is another sectional view of the valve similar to Figure 1, the operative parts thereof

2

being shown in a different functional but closed relationship.

Figure 3 is another view similar to Figure 1, likewise showing the parts in a different functional and open relationship.

Figure 4 is a sectional view taken as on a line 4—4 of Figure 3.

Figure 5 is a sectional view of another form of valve embodying this invention.

Figure 6 is a sectional view taken as on a line 6—6 of Figure 5.

Figure 7 is a sectional view of a further modified form of valve embodying this invention.

Figure 8 is another further modified form of this invention in sectional view.

Figure 9 is a sectional view taken as on a line 9—9 of Figure 8.

Referring more particularly to the drawings, there is illustrated by way of example, but not of limitation, a control valve, generally designated by the numeral 20, secured in any conventional manner to a flexible rubber hose 22, as by set screws 23 provided in any desired number therearound.

25 The valve 20 preferably comprises a body 25 of cylindrical form including a plug 26 secured within the body as by set screws 27. The plug 26 is threaded as at 28 to permit the axial threaded insertion of a complementarily threaded nozzle 30 formed as with raised male threads 31.

The body 25 of the valve is fitted with a preferably replaceable rubber lining 33 which makes a tight fit around its circumferential periphery 34 with the inner walls 35 of the body 25.

35 The liner 33 is formed as with a rearwardly extending portion 36 communicating directly with the interior 37 of the hose or the like 22 and a preferably forwardly extending portion 38. At its forward end 39 the liner is most desirably stepped and abuts a rubber collar 40 formed separately therefrom for convenience of manufacture, said collar having a rearwardly directed annular preferably flared cavity 42 for the receipt of the rearmost portion 43 of the nozzle 30.

40 45 The collar 40 is fluid tight around the nozzle portion 43 and is shaped to promote the least amount of fluid friction.

The liner 33 includes, integrally therewith, a flexible diaphragm 44 including central solid portions 45, 48 and axially directed ports 46 of suitable hydrodynamic shape communicating between the rearward and forward sides of the valve. Said ports 46 are preferably uniformly distributed circumferentially of the axis of the valve and are of any desired shape preferably to offer

the least possible resistance to a flow there-through. A rearwardly directed thickened and suitably streamlined portion 48 may be formed integral with the central portion 48 of the dia-phragm.

The nozzle 30 is preferably formed with a flared opening 50 and a central bore 51 continuous therewith and is lined with a hardened layer 53 such as tungsten carbide.

The rearmost end 43 of the nozzle is adapted to seat against the central portion 48 of the dia-phragm 44 in at least one operative position of axial extension of the nozzle within such body wherein the valve is closed (c. f., Figures 1 and 2).

The normal fluid pressure from the hose 22 against the back side of the diaphragm distorts or flexes the diaphragm as at 55 forwardly (Figure 2) causing the same to seat against the end 43 of the nozzle. The normal unflexed position of the diaphragm is shown in Figure 3. The re-silient forces within the diaphragm resisting deflection cause the same to snap closed suddenly against the end 43 of the nozzle when the dia-phragm is moved close to the end 54 of the nozzle.

The valve is also suddenly opened (i. e., with a "snap") releasing the full force of the sand blast as the nozzle is moved axially away from the dia-phragm, as by unthreading movement of the nozzle.

In the above described snap action of the dia-phragm when the nozzle 30 is axially moved within the body relative to the diaphragm, a point is reached in which the diaphragm suddenly snaps closed against the end 54 of the nozzle. Such snap action is effected instantaneously so that the full blast is suddenly released or it is equally suddenly stopped. No dribbling of sand and/or water or other conveyed material there-by occurs.

The path of the blast is from the hose 22 through the end portion 36 of the liner 33, the ports 46, the annular tapered surge chamber 57, through the tapered opening 50 and bore 51 of the nozzle.

A hose 60 conducts fluid, such as water, into the nozzle 30 through a needle valve 61, and a nipple 62 passing through the wall of the body 25 with clearance to permit slight lateral and tilting movement thereof when the diaphragm flexes. The interior 63 of the nipple is formed with an extension 64 providing an orifice 65 co-axial with the nozzle and projecting thereinto for introducing a jet or spray of water or the like at the most propitious time and position when using the nozzle for a cement gun or otherwise for wetting the blasting agent.

It is preferable that the hydro-dynamics of the nozzle be enhanced by extending the central part of the diaphragm forwardly to form a coni-cal portion 66 around the extension 64.

In order to disassemble the valve the nozzle 30 may be merely axially removed by unthreading and may then be replaced or repaired as desired. Furthermore, a nozzle containing a different sized bore may be substituted. In this manner, the nozzle, which tends to be eroded internally usually prior to the wearing out of the other parts, particularly the body 25, may be replaced without discarding the relatively unworn balance of the valve.

The plug 26 may be removed through removal of the set screws 27 whereupon the liner 33 may be axially withdrawn from the body 25 for re-

pair or replacement. But particularly the ring 40 and the liner 36 may be axially withdrawn from the body 25 as through removal of the valve from its connection with the hose 22 or by removal of the plug 26 and thereby replaced when worn.

In the embodiment of Figures 5 and 6 a valve generally designated at 100 may be threadedly or otherwise secured to hoses or pipes 101 and 102 connected to a source and outlet respectively of air, water, oil, or other fluid carrying suspended material such as sand, grit, dirt, or the like.

The valve body 103 may be substantially globe-shaped. A stem 104 may be threadedly or slidably inserted as through a bore 105 (threaded as shown), formed in the body 103 and axially manipulatable as by a handle 106 of a threaded type or of a quick-acting or lever type. By a ball and socket or equivalent connection 107, axial movement of the stem 104 may be transmitted through core 108 to a rubber diaphragm 109 formed integral with a liner 110. The diaphragm 109 can include a forwardly directed tapered valve portion 111 having a preferably fluted exterior surface 112 adapted to be compressed in seating against an annular seat 113 formed as by a tapered bore 114 in the end 115 of the outlet pipe 116. The pipe 116 and the pipe 102 may be integral or may be formed of separate portions so that the pipe 116 is a replaceable insert for the valve. Also, the seat 113 and diaphragm 109 may be set at an angle relative to the axis of the valve corresponding to that of the stem 104 so that such stem is approximately normal to the plane of the diaphragm and seat and is axially related to them.

The flow of fluid containing suspended ma-terial is through the pipe 101 into the interior 118 of the valve body 103 provided with its prefer-ably replaceable rubber lines 110, thence through ports 119 in the liner to the forward side of the diaphragm which may in part form an annular surge chamber 120 whence the material is passed through the pipe 116 between the seat 114 and the tapered valve element of deformable rubber or similar material 112.

The valve may be forcibly closed against sus-pended material carried by the fluid without injury to the valve or its parts. The fluted core-like valve portion 112, being capable of compres-sion, is smashed against the seat 113. Due to the lining and integral diaphragm construction which is resistant to erosion, the valve possesses a particularly long life and high service qual-ities and is adapted for use in sand blasting as well as for conducting other fluids containing suspended matter. The fluted arrangement of the cone-shaped seat 112 facilitates the break-ing away thereof from the seat-annulus 114.

In the embodiment of Figure 7 a valve 150 comprises a body 151 secured to a hose or pipe 152, a liner 153 of rubber or other suitable de-formable resilient material and a nozzle 154.

The body 151 may have a rounded end 155 which is thickened for threading at 156 to accommodate the male threads 157 upon the nozzle.

The liner 153 may as in the previous embodi-ments likewise be formed with an integral dia-phragm or partition 158 including ports 159 communicating between a rearmost chamber 160 and a foremost chamber 161, the latter defining a surge chamber. The diaphragm 158 may be de-formable axially as in the preceding embodi-ments and may be provided with an iron core 162 into which a rod 163 is threaded at its end 164.

The foremost end 165 of the rod is deformed in a manner known to those skilled in the art for regulating the nature of the stream emitted from the end 166 of the nozzle. In the instant embodiment axial movement of the nozzle relative to the body through the threads 156 and 157 causes the rear or inner end 168 of the nozzle to engage against the forwardly directed cone 169 on the diaphragm 158 for the regulation of the volume or quantity of the flow. A rearwardly directed cone 170 formed on the diaphragm 158 provides a more or less streamlined appearance for the diaphragm minimizing the effectiveness, if desired, of any snap action of the diaphragm by permitting a more gradual adjustment of the amount of fluid volume issuing through the nozzle. As illustrated, any snap action, due to the thickness of the diaphragm, is only slight.

The end 166 of the nozzle is adjustable, as by threading at 171, for extension from the main body of the nozzle 154, in order to control the nature of the emitted stream.

Thus a spray may be had, or a relatively heavy stream by adjusting the end 166 relative to the end 165 of the rod, the volume being separately controlled by axial adjustment of the main nozzle body as by the threads 156, 157.

For abrasive materials carried in the fluid, a liner as of tungsten carbide 172 is provided within the bore 173 of the nozzle.

As heretofore explained, the replaceable rubber liner 153 minimizes the erosion due to abrasive action within the body 151 of the valve. The nozzle 154, including the end or tip 166, the liner 153, and the valve body 151, as well as the rod 163, are replaceable.

In the embodiment of Figure 8 the valve 200 comprises a body 201, a forward plug 202 keyed thereto as by screws 203, a nozzle 204 axially threadable within the plug 202 and a rubber liner 205.

The rubber liner comprises a body portion 206 and a diaphragm 207 formed with a passageway 208 defining an orifice 209 connected with a hose 210 leading as to a source of water.

The nozzle 204 may be constructed as in the previous embodiments, particularly as in the embodiment of Figures 1 through 4 and is similarly adapted to engage against the diaphragm 207 or the cone-shaped forward projection 211 thereof as and for a valve or regulating mechanism, with or without snap action.

The incoming fluid through the hose 210 may be adjusted as by a needle or other valve 212 from which it is directed under pressure through the orifice 209 into the bore 213 of the nozzle 204. Thus it may readily be picked up by the incoming relatively dry air and sand customarily delivered by the hose 214. Such dry sand and air is fed through ports 216 formed in the diaphragm 207, such ports being relatively tapered inwardly and forwardly to provide a more direct and streamlined passage for the dry ingredients from the hose 214 to the nozzle 204, thereby practically omitting the surge chamber provided in the other embodiments as at 215.

Obviously, the water injector system through the orifice 209 will not be operative unless the water pressure is sufficient to overcome the pressure of the air and other dry ingredients 214 through the ports 216 and the bore 213 of the nozzle, having due regard for any venturi effect occasioned by the construction of the parts at and around the orifice 209.

By the instant construction, an excellent co-

mingling of the dry and wet ingredients is occasioned, and the resultant valve is well adapted for use as a dry blast or wet blast control.

It may be noted that the radially inserted injector pipe 220 including the axially directed extension thereof 221 leading to the orifice 209 would, if made of metal or other inflexible material, prevent the axial movement or deformation of the diaphragm for the snap-action opening and closing of the valve as aforesaid. Therefore, if the snap action be desired in the instant valve, the passageway 208 may be formed directly in the diaphragm 207 or said passageway may be lined with a flexible metal conduit or with a flexible sheath of rubber of the like material. Preferably the opening 209 should be fairly well formed of relatively hard stock to improve its function as an orifice.

The nozzle 204 may have a removable tip 226 which together with the main body 227 of the nozzle comprise a holder or chamber for the confinement of a plurality of annular bodies or washers, as of plastic, 228 positioned in abutting coaxial relationship to one another within the nozzle 225. The first of such bodies 228 is held firmly against axial movement by means of the shoulder 229 formed in the tip 226 of the nozzle while the rearmost of such washers 230 is likewise clamped and firmly held by means of the annular shoulder 231 formed adjacent the nozzle inlet 232. The bodies 228 may be formed as annuli or as radially separated liner segments. Threads 233, for example, may be provided on the nozzle adjacent its inlet 232 for securing the nozzle adjustably to a valve body as in the previous embodiments.

While turbulence of the fluid passing through the ports formed in the diaphragm of the various embodiments of the valves herein described is sometimes desirable, it is of equal and probably greater importance to avoid such turbulence as would drive the particles suspended to the incoming fluid laterally against the interior of the nozzle or pipe, comprising the valve outlet. Since such lateral movement tends to cause undue erosion of the interior of the nozzle or outlet pipe, the degree of turbulence can be regulated to a large extent by appropriate streamlining of the cones formed upon the inlet or outlet side of the diaphragm, or both. Likewise, the size and shape of the ports through the diaphragm, including the intervening diaphragm material between ports, is of importance and is often critical in achieving an optimum streamlined and unobstructed passage of the fluid, such as air and sand.

The form and construction of the various nozzles and outlet pipe herein illustrated and described are not intended to relate only to the particular embodiment in which they are shown but may to a large extent be rendered interchangeable through modification within the skill of one familiar with the art of valve construction.

This invention features the provision of a new and improved valve suitable for controlling, stopping and starting the flow of a fluid containing abrasive or other suspended foreign matter. It likewise features the provision of a perforated preferably flexible diaphragm having a solid center axially disposed in a conduit having an end sealable against the solid center of the diaphragm as and for the valve means per se, the conduit being axially adjustable. It likewise features the provision of a diaphragm having an optionally

adjustable preferably snap action for instantaneously turning on and shutting off the full force of the desired fluid stream. In addition, the invention features the provision of a new and improved axially disposed liquid injector of maximum effectiveness, an optional cone-shaped substantially streamlined central diaphragm portion, and replaceable rubber or hardened parts or the like.

While I have herein shown and described my invention in what I have conceived to be the most practical and preferred embodiment, it is recognized that departures may be made therefrom within the scope of my invention, which is not to be limited to the details disclosed herein, but is to be accorded the full scope of the claims so as to embrace any and all equivalent devices.

The invention having been herein described, what I claim as new and desire to secure by Letters Patent is:

1. In a valve, for the control of a fluid containing an abrasive such as sand, and including a hollow valve body, rubber liner means disposed within the body substantially lining the interior thereof, a fluid inlet, and a fluid outlet spaced from the fluid inlet, said liner means including a resilient diaphragm extending across the interior of the body between said inlet and said outlet, nozzle means in the outlet axially extensible within the body, the inner end of said nozzle being adapted to move relatively toward and away from the diaphragm and being further adapted to seat and close against the diaphragm in at least one position of axial extension of the nozzle, said diaphragm being formed with passageways communicating between opposite sides of the diaphragm to permit a fluid normally to pass from the inlet to the outlet of the valve, and including a solid central portion adapted to seat against said nozzle to close the same.

2. In a valve, for the control of a fluid containing an abrasive such as sand, and including a hollow valve body, rubber liner means disposed within the body substantially lining the interior thereof, a fluid inlet, and a fluid outlet spaced from the fluid inlet, said liner means including a resilient diaphragm extending across the interior of the body between said inlet and said outlet, nozzle means in the outlet axially extensible within the body, the inner end of said nozzle being adapted to move relatively toward and away from the diaphragm and being further adapted to seat and close against the diaphragm in at least one position of axial extension of the nozzle, said diaphragm being formed with passageways communicating between opposite sides of the diaphragm to permit a fluid to pass from the inlet to the outlet of the valve, said diaphragm being deflectable and having a portion adapted to seat against the inner end of the nozzle when said nozzle end is moved in a position of proximity to the diaphragm under the influence of fluid pressure passing from the inlet to the outlet.

3. In a valve for the control of a fluid containing an abrasive such as sand, and including a hollow valve body, rubber liner means disposed within the body substantially lining the interior thereof, a fluid inlet, and a fluid outlet spaced from the fluid inlet, said liner means including a resilient diaphragm extending across the interior of the body between said inlet and said outlet, nozzle means in the outlet axially extensible within the body, the inner end of said nozzle being adapted to move relatively toward and away from the diaphragm and being further adapted to seat

and close against the diaphragm in at least one position of axial extension of the nozzle, said diaphragm being formed with passageways communicating between opposite sides of the diaphragm to permit a fluid to pass from the inlet to the outlet of the valve, said diaphragm being deflectable and adapted to seat with a snap against the inner end of the nozzle when said nozzle end is moved into a position of proximity to the diaphragm under the influence of fluid pressure passing from the inlet to the outlet.

4. In a valve for the control of a fluid containing an abrasive such as sand, and including a hollow valve body, rubber liner means disposed within the body substantially lining the interior thereof, a fluid inlet, and a fluid outlet spaced from the fluid inlet, said liner means including a resilient diaphragm extending across the interior of the body between said inlet and said outlet, nozzle means in the outlet axially extensible within the body, the inner end of said nozzle being adapted to move relatively toward and away from the diaphragm and being further adapted to seat and close against the diaphragm in at least one position of axial extension of the nozzle, said diaphragm being formed with passageways communicating between opposite sides of the diaphragm to permit a fluid to pass from the inlet to the outlet of the valve, said diaphragm being deflectable and adapted to seat with a snap against the inner end of the nozzle when said nozzle end is moved into a position of proximity to the diaphragm under the influence of fluid pressure passing from the inlet to the outlet, said diaphragm being caused to snap open away from said nozzle upon axial extension of said nozzle in said outlet away from said diaphragm against said fluid pressure on account of the inherent resilience of the diaphragm.

40 5. A valve as characterized in claim 4, including manually operable control means normally restraining said diaphragm from said seating or opening movement, but manually operable to permit said deflection of said diaphragm toward and away from the inner end of the nozzle to close or open the same as desired.

6. A valve as characterized in claim 4, said diaphragm being formed with a substantially cone-shaped projection coaxial with the inlet and outlet adapted to seat in the outlet in a closed position of the valve.

7. A valve as characterized in claim 4, manually adjustable means for urging said diaphragm toward and away from the inner end of the nozzle to close or open the same as desired.

55 8. A valve as characterized in claim 1, water injection means, including a passageway formed within the diaphragm, said passageway including an orifice directed into the inner end of said nozzle, whereby water may be supplied to a fluid passing from the inlet to the outlet of the valve, and manually controllable means in the water injector means for controlling the flow of water through said orifice.

65 9. In a valve for the control of a fluid containing an abrasive such as sand, and including a hollow valve body, a fluid inlet, and a fluid outlet in coaxial alignment on opposite sides of the valve body, said liner means including a diaphragm extending across the interior of the body between said inlet and said outlet substantially normal to the axis thereof, nozzle means in the outlet axially extensible within the body, the inner end of said nozzle being adapted to move relatively toward and away from the diaphragm under the influence of fluid pressure passing from the inlet to the outlet, said diaphragm being formed with passageways communicating between opposite sides of the diaphragm to permit a fluid to pass from the inlet to the outlet of the valve, said diaphragm being deflectable and adapted to seat with a snap against the inner end of the nozzle when said nozzle end is moved into a position of proximity to the diaphragm under the influence of fluid pressure passing from the inlet to the outlet.

and being further adapted to seat and close against the diaphragm, said diaphragm being formed with passageways communicating between opposite sides of the diaphragm to permit a fluid to pass from the inlet to the outlet of the valve, said diaphragm being deflectable and adapted to seat with a snap against the inner end of the nozzle under the influence of fluid pressure passing from the inlet to the outlet, said diaphragm being caused to snap open away from said nozzle upon axial extension of said nozzle in said outlet away from said diaphragm against said fluid pressure on account of the inherent resilience of the diaphragm.

10. The structure of claim 9 further characterized by water injection means including a passageway formed within the diaphragm, said passageway including an orifice directed into the inner end of said nozzle whereby water may be supplied to a fluid passing from the inlet to the outlet of the valve and manually controllable means in the water injector means for controlling the flow of water through said orifice.

11. In a fluid controlled valve of the character described comprising a valve body, a fluid inlet in the body and a fluid outlet on the opposite side of the valve from said inlet including a nozzle axially adjustable within such outlet, a rubber diaphragm extending across the valve body between the inlet and the outlet, said diaphragm having a solid central portion and being formed with ports communicating between opposite sides of said diaphragm in a direction substantially paralleling axis in the valve, said diaphragm being adapted for axial deformation to seat against the inner end of the nozzle for closing the valve, said diaphragm being normally in a relatively deformed position against the inlet when said valve is closed and being adapted to snap away from said outlet to open the valve upon axial extension of the nozzle due to the inherent resilience of the diaphragm.

12. In a fluid controlled valve of the character described comprising a valve body, a fluid inlet in the body and a fluid outlet on the opposite side of the valve from said inlet including a nozzle axially adjustable within such outlet, a rubber diaphragm extending across the valve body between the inlet and the outlet, said diaphragm having a solid central portion and being formed with ports communicating between opposite sides of said diaphragm in a direction substantially paralleling axis in the valve, said diaphragm being adapted for axial deformation to seat against the inner end of the nozzle for closing the valve, said diaphragm being normally in a relatively deformed position against the inlet when said valve is closed and being adapted to snap away from said outlet to open the valve upon axial extension of the nozzle due to the inherent resilience of the diaphragm, said nozzle being replaceable and comprising a casing, a hard core of abrasive resistant material forming the nozzle port.

13. In a fluid controlled valve of the character described comprising a valve body, a fluid inlet in the body and a fluid outlet on the opposite side of the valve from said inlet including a nozzle axially adjustable within such outlet, a rubber diaphragm extending across the valve body between the inlet and the outlet, said diaphragm

having a solid central portion and being formed with ports communicating between opposite sides of said diaphragm in a direction substantially paralleling axis in the valve, said diaphragm being adapted for axial deformation to seat against the inner end of the nozzle for closing the valve, said diaphragm being normally in a relatively deformed position against the inlet when said valve is closed and being adapted to snap away from said outlet to open the valve upon axial extension of the nozzle due to the inherent resilience of the diaphragm, said nozzle being replaceable and comprising a casing, a hard core of abrasive resistant material forming the nozzle port, and comprising a coaxial stack of plastic washers.

14. In a valve for the control of a fluid containing an abrasive such as sand, and including a hollow valve body, rubber liner means disposed within the body substantially lining the interior thereof, a fluid inlet, and a fluid outlet spaced from the fluid inlet, said liner means including a resilient diaphragm extending across the interior of the body between said inlet and said outlet, nozzle means in the outlet axially extensible within the body, the inner end of said nozzle being adapted to move relatively toward and away from the diaphragm and being further adapted to seat and close against the diaphragm in at least one position of axial extension of the nozzle, said diaphragm being formed with passageways communicating between opposite sides of the diaphragm to permit a fluid to pass from the inlet to the outlet of the valve, a rod extending from the diaphragm axially through the nozzle, a tip on the rod and an axially adjustable end on the nozzle adapted by coaction to regulate the character of the flow from the nozzle.

15. In a valve, for the control of a fluid containing an abrasive such as sand, and including a hollow valve body, rubber liner means disposed within the body substantially lining the interior thereof, a fluid inlet, and a fluid outlet spaced from the fluid inlet, said liner means including a resilient diaphragm extending across the interior of the body between said inlet and said outlet, said outlet including a seat, said diaphragm being formed with passageways communicating between opposite sides of the diaphragm to permit a fluid to pass from the inlet to the outlet of the valve, said diaphragm being deflectable and having a portion adapted to seat against the seat of said outlet when said diaphragm is deflected towards and against said outlet seat.
